(57) **CLAIM**

The ornamental design for an electric hair clipper with integrated wireless camera, as shown and described.

DESCRIPTION

FIG. 1 is a front, top and right side perspective view of the electric hair clipper according to our new design with the integrated wireless camera in a retracted or closed state; FIG. 2 is a left side elevational view of the electric hair clipper with the integrated wireless camera in the closed state;

FIG. 3 is a right side elevational view of the electric hair clipper with the integrated wireless camera in the closed state;

FIG. 4 is a front elevational view thereof;

FIG. 5 is a rear elevational view thereof;

FIG. 6 is a top view thereof;

FIG. 7 is a bottom view thereof;

FIG. 8 is a front, top and right side perspective view of the electric hair clipper with the integrated wireless camera in an extended or open state;

FIG. 9 is a left side elevational view of the electric hair clipper with the integrated wireless camera in the open state; FIG. 10 is a right side elevational view of the electric hair clipper with the integrated wireless camera in the open state;

FIG. 11 is a front elevational view thereof;

FIG. 12 is a rear elevational view thereof;

FIG. 13 is a top view thereof; and,

FIG. 14 is a bottom view thereof.

The broken lines shown in FIGS. 1, 6, 8 and 13 indicating charge level lighting and in FIGS. 5 and 12 indicating a charge port form no part of the claimed design.
